(57) **CLAIM**

The ornamental design for an electronic device or portion thereof with animated graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of an electronic device or portion thereof with animated graphical user interface showing our new design;

FIG. 2 is a front view of a second image thereof;

FIG. 3 is a front view of a third image thereof;

FIG. 4 is a front view of another embodiment thereof;

FIG. 5 is a front view of a second image thereof; and,

FIG. 6 is a front view of a third image thereof.

The peripheral dashed broken lines illustrate a display screen or portion thereof, and form no part of the claimed design.

The appearance of the graphical user interface transitions between the images shown in FIGS. 1-3. The appearance of the graphical user interface transitions between the images shown in FIGS. 4-6. The process or period in which one image transitions to another forms no part of the claimed design.
